Filed Oct. 27, 1966, Ser. No. 589,901
9 Claims. (Cl. 108—152)

ABSTRACT OF THE DISCLOSURE

A shelf mounting comprising an elongated strip having a top ridge and having an inner edge adapted to bear against the wall which is greater depth than its outer edge, securing screws extending through the mounting strip below the ridge, and a shelf of uniform cross-section having a bottom recess at its inner edge shaped to interfit with the mounting strip and its ridge, the inner edge of the shelving being of increased thickness to conceal the screw heads and to provide increased bearing surface, with the increased thickness of the shelf merging into said increased thickness at the bottom of the mounting strip.

Summary

Heretofore shelves have been difficult to install and there have been complicated connecting means for making a connection between the inner edge of the shelf and the wall. The present invention provides a shelf construction where a mounting strip can be connected by screws to the wall and where the shelf has its inner edge so recessed as to interfit with the cross-sectional shape of the mounting strip to cover the mounting strip screws and provide a strong bearing surface for the shelf, the mounting strip also having a cross-sectional shape to provide a bearing surface throughout its length below the screws. With this arrangement, once the mounting strips are in place, a shelf can be attached without tools to a mounting strip in such a way that the mounting strip is unnoticeable.

A primary object of the present invention is to provide a mounting of shelves for use on any vertical wall presenting no visible means of support for the mounted shelves, and which eliminates the usual metal brackets or the like customarily required for the support of wall mounted shelves.

A further object of the invention is to provide shelf mountings including shelving and mounting strips, both of which can be sold by a lumber dealer or supplier in any stated lengths and then be subsequently sawed off by the user to fit his particular requirements.

A further object of the invention is to provide shelf mountings wherein shelves can be very expeditiously and easily mounted on a vertical wall of a room and can be quickly removed when required.

A further object of the invention is to provide a shelf mounting which results in very neat and attractive wall mounted shelves devoid of visible brackets, screws and other external mounting means.

A further object of the invention is to provide a shelf mounting for a room wall including a mounting strip and a specially formed shelf member wherein, when the assembly is completed, the mounting strip is invisible and merges into the inner edge portion of the shelf.

A further object of the invention is to provide a shelf mounting which is neat and attractive in appearance, is relatively inexpensive, is strong and rigid, which is easy to assemble and mount or disassemble, and which is well adapted for the purposes described.

With the above and other objects in view the invention consists of the improved shelf mounting and its parts and combinations as set forth in the claims, and all equivalents thereof.

2

In the accompanying drawing in which the same reference characters indicate the same parts in all of the views:

FIG. 1 is a fragmentary perspective view, partly in section, showing the shelf mounting strip applied to the vertical wall facing of a room, the wall facing in turn being mounted on spaced-apart, vertical 2 by 4's;

FIG. 2 is a fragmentary perspective view showing a portion of a piece of shelving engaged by the mounting strip, the vertical supports and wall facing being omitted; and

FIG. 3 is an enlarged vertical sectional view taken approximately along line 3—3 of FIG. 1, only also showing section the shelving carried by the mounting strip.

Within the contemplation of the present invention the improved shelf mounting is adapted to be applied to the face of any vertical wall. The wall may take the form of a planked wood wall, or the shelving may be mounted on a plaster wall or any type of dry wall construction. Merely by way of example there is illustrated in FIGS. 1 and 3 a wall construction wherein there are vertical 2 by 4's, indicated by the numeral 6, at 16" intervals. In the embodiment illustrated these spaced vertical supports 6 have secured thereto a facing 7 of plasterboard or other suitable material.

The numeral 8 indicates a novel form of elongated mounting strip which is adapted to be secured to the facing material 7 at a desired elevation and to the uprights 6 by means of screws 9 which pass through openings 10 therefor in the mounting strip 8, the heads of the screws 9 being countersunk as shown. The mounting strip is of wood or other suitable material and can be secured from a lumber dealer or supplier in a desired length to be subsequently sawed to the final required length by the installer. The top edge of the mounting strip 8, coextensive with its length, is formed with a shouldered recess 11 to provide forwardly thereof an upstanding tenon ridge 12. The mounting strip is of substantial depth. Preferably the lower surface of the mounting strip 8 is beveled or curved on a radius, as shown at 13, and the height of the inner face of the strip 8 is, by way of example 1", and the upstanding tenon ridge 12 projects upwardly $\frac{3}{8}$ ". The front or outer face of the mounting strip 8 should be about $1\frac{1}{8}$ " in height, and the overall breadth of the mounting strip is approximately $3\frac{1}{4}$ ".

An extent of shelving to be mounted on the mounting strip 8 for horizontal projection into the room from the wall facing 7 is indicated generally by the numeral 14. The shelving can be formed of wood or other suitable material and is preferably about 9" wide and can be furnished to the installer or cut by him in a desired length to conform with the overall length of the shelf desired and to the ultimate length of the mounting strip 8. The shelving has increased thickness adjacent the mounting strip. In the preferred form illustrated, the shelf 14 at its front edge is preferably about $3\frac{1}{4}$ " thick, but from its front edge, as indicated at *a* in FIGS. 2 and 3, to about the point *b*, toward the rear in said figures, the shelf becomes progressively thicker, so that at point *b* it has a thickness of approximately $1\frac{1}{8}$ ". The lower face of the shelving to provide the taper may be plane or on a slight curvature. Extending lengthwise adjacent the inner edge of the shelving 14, from the bottom upwardly, is a shouldered recess 15 (see FIGS. 2 and 3) which is shaped and proportioned to exactly receive therein the connecting means of the mounting strip, which in the preferred form illustrated is a tenon ridge 12 on the top of the mounting strip 8 with an elongated recess 11 therebehind.

In order to assemble the components of the shelving and to mount the same on the wall facing 7, the desired length of mounting strip 8 is applied to the wall face 7 and uprights 6 in the manner previously described and

as is illustrated in FIG. 1. Next, an extent of shelving 14, to provide a shelf of the proper length and corresponding to the length of the mounting strip, is easily manually engaged with the secured mounting strip, as shown in FIGS. 2 and 3, the recessed and shouldered portion 15 of the shelving engaging the complementary tenon and recessed portions of the mounting strip so that the mounting strip and inner edge portion of the shelving are to all intents and purposes integral with the mounting strip being engaged within the recessed inner edge portion of the shelving and hence not visible when the installation is completed. The recess of the shelving has a forward, vertically disposed, elongated bearing wall 16 which meets the front face of the mounting strip and corresponds thereto in height, and in the preferred embodiment illustrated the downwardly curved or tapered bottom portion 13 of the mounting strip forms a flush continuation of the thickened inner portion of the bottom of the shelving and merges therewith.

By virtue of the fact that the shelving is considerably thicker near the mounting strip and in the preferred embodiment extends $\frac{3}{8}$ " above the tenon ridge 12 on the mounting strip, when weight is imposed on the top surface of the shelving 14 any tendency of the shelving to pivot on its mounting is eliminated because of the lowered location of the fulcrum point. The wide composite inner face, afforded by the inner end of the shelving plus the thickened inner face of the mounting strip, increases the effective bearing surface relative to the wall facing and results in a very rigid and stable shelf which will support a relatively heavy load without the need for external braces or supports.

The improved shelf mounting is very neat and attractive in appearance and is easy to assemble and install or to disassemble. It is furthermore inexpensive and is well adapted for the purposes set forth.

What I claim is:

1. A shelf construction comprising in combination a mounting strip having an elongated inner face, having an outer face, and having a top surface provided with an elongated upstanding ridge spaced outwardly from said inner face to provide an elongated recess behind the ridge, securing elements extending inwardly from the outer face of the mounting strip through the latter at spaced intervals below the mounting strip recesses, said 45 mounting strip being adapted to be attached to a wall by said securing elements with said elongated inner face in contact with the wall, a shelf of uniform cross section substantially throughout its length having an inner edge and having a bottom recess communicating with said inner edge, which recess has a cross-sectional shape so that the inner edge of the shelf removably and snugly interfits by downward movement with the ridge and recess on the top surface of the mounting strip, with the inner edge of the shelf being adapted to abut the wall, said bottom recess of the shelf having a forward, vertically-disposed,

elongated bearing wall throughout the length of the shelf which is in contact throughout the length of the shelf with the elongated outer face of the mounting strip in assembly, the shelf being of increased thickness throughout its length adjacent said bearing wall and mounting strip so that said bearing wall is of increased depth sufficient to project a substantial distance below the bottom of the elongated recess of the mounting strip.

2. A shelf construction as defined in claim 1 in which the bearing wall of the shelf recess projects downwardly a sufficient distance to cover the securing elements.

3. A shelf construction as defined in claim 1 in which the elongated inner face of the mounting strip which is in contact with the wall has sufficient depth to project downwardly below the lowermost portion of the outer face of the mounting strip to provide increased bearing surface for said inner face.

4. A shelf construction as claimed in claim 1 in which the front of the elongated ridge of the mounting strip is flush with the outer face of the mounting strip and in which the bearing wall of the recess of the shelf also bears against said front of the ridge.

5. A shelf construction as claimed in claim 1 in which the inner face of the mounting strip depends a substantial distance below its outer face and below the greatest thickness portion of the shelf.

6. A shelf construction as claimed in claim 1 in which the inner face of the mounting strip depends a substantial distance below its outer face and below the greatest thickness portion of the shelf and in which the lower surface of the mounting strip is shaped to merge with the bottom of the shelf.

7. A shelf construction as claimed in claim 5 in which said bottom surface of the mounting strip is curved into said merging relationship.

8. A shelf construction as claimed in claim 7 in which the inner portion of the lower surface of the shelf is curved in said merging relationship with the bottom surface of the mounting strip.

9. A shelf construction as claimed in claim 1 in which the mounting strip provides the sole means for securing the shelf to a wall and for supporting it.
